No. 733,132.

PATENTED JULY 7, 1903.

W. W. BRADLEY.
ADJUSTABLE WICK RAISER.
APPLICATION FILED APR. 27, 1903.

NO MODEL.

UNITED STATES PATENT OFFICE.

WILLIAM W. BRADLEY, OF WATERBURY, CONNECTICUT, ASSIGNOR TO THE PLUME AND ATWOOD MANUFACTURING COMPANY, OF WATERBURY, CONNECTICUT, A CORPORATION OF CONNECTICUT.

ADJUSTABLE WICK-RAISER.

SPECIFICATION forming part of Letters Patent No. 733,132, dated July 7, 1903.

Application filed April 27, 1903. Serial No. 154,508. (No model.)

To all whom it may concern:

Be it known that I, WILLIAM W. BRADLEY, a citizen of the United States, residing at Waterbury, in the county of New Haven and

5 State of Connecticut, have invented an Improvement in Adjustable Wick-Raisers, of which the following is a specification.

My invention relates to a wick-raiser especially adapted for Argand lamps, the same 10 having an adjustable function—that is, the possibility of arresting the movements of the wick and especially the upward movement of the wick at the desired or a predetermined position, according to the height of the flame 15 desired.

In carrying out my invention I apply to the shaft of the pinion a frictionally-held device 20 or friction-clamp, which turns with the said shaft and pinion and stops against the lamp-body in either one of two positions, and so determines the limits of movement of the wick. The friction-clamp holds sufficiently 25 tight upon the shaft to arrest the movement of the shaft and the parts actuated thereby; but the application of force to the shaft when said friction-clamp stops at either of its positions against the lamp-body causes the said shaft to slip in the friction-clamp, thereby 30 changing the position of the clamp with reference to the shaft and at the same time effecting a change in the relation of the wick to the wick-tube.

In the drawings, Figure 1 is a vertical section and partial elevation through the upper 35 portion of the font or lamp-body and the parts adjacent thereto. Fig. 2 is a sectional plan at $x-x$ of Fig. 1, and Fig. 3 is a vertical section through one side of the structure approximately on the line $y-y$ of Fig. 2.

40 a represents the wick-tube of the lamp; a' , the wick; a^2 , the font of the lamp; b , the air-distributer; c , the central draft-tube, and d a tube surrounding the wick and provided with series of perforations, any one of which 45 is adapted to form the rack. These parts are of ordinary and well-known construction.

e represents the shaft, e' the pinions secured thereto and which mesh with the perforations of the tube d for raising and lower-

ing the said tube d and with it the wick. On 50 the outer end of this shaft e there is a knurled disk e^2 of usual construction to be grasped by the fingers.

2 represents a bearing-bracket connected to and within the font of the lamp and acting 55 as a substantially central or intermediate support for the shaft e , said shaft having an end bearing 3 in the font and passing through the tubular support f , which is secured to the font of the lamp and incloses the said shaft 60 for the major portion of its length. The inner free end of this tube comes into close proximity with one of the pinions e' , while the bearing-bracket 2 comes into close proximity with the opposite side of the adjacent 65 pinion. Thus the pinions are held between and guided by the end of the said tubular support f and the bearing-bracket 2.

h represents an adjustable friction-clamp. This device comprises a sleeve extending 70 around the shaft with lug extensions, through which passes a rivet or screw 4. The lug extensions of this structure do not quite come together, so that the screw which passes freely through one of said extensions passes 75 into an interiorly-threaded aperture in the other extension and tension applied by the rivet or screw tends to draw said lug extensions together, so as to clamp the sleeve portion tightly upon the shaft e . Sufficient tension could be applied to the rivet or screw 80 to clamp the sleeve so firmly to the shaft e that it would be impossible to turn the shaft with relation to the clamp; but this is not the intention, as sufficient tension is to be 85 applied to prevent the shaft turning with relation to the clamp upon the application of the ordinary pressure or force that would be made in raising and lowering the wick and in the stoppage or arresting of the movement 90 of the parts connected therewith.

As shown especially in Figs. 1 and 3, it will be noticed that in one position said clamping device h comes against the font or body of the lamp adjacent to the tube d , and 95 in the other position after slightly more than a half-revolution has been given to the shaft e the said parts come against the lamp-body

nearer the surface or distant from said tube *d*. When this friction device *h* stops in either of these positions, the movements of the tube *d* and the wick *a'* are arrested and 5 the extent to which this device permits the shaft *e* to turn controls the extent of vertical movement of the wick *a'*.

In the use of the lamp when the wick becomes too low and requires to be raised the 10 shaft is to be turned until said friction device or clamp *h* comes against the body of the lamp in the position shown in full lines Fig. 3 and dotted lines Fig. 1. When in this position, the application of force to the shaft 15 causes the same to slip in this friction-clamp in proportion to the force applied and the continuation thereof, as applied to the shaft and the knurled head in a circular direction. The wick is thus raised to the desired height. 20 The release of pressure permits the friction device to hold just as firmly to the shaft as before and with sufficient force to ordinarily arrest the upward movement of the wick. Should the wick be too high, the further 25 lowering of the same is effected by applying force to the shaft after the friction device thereon comes into the dotted position, Fig. 3, the further movement of the shaft causing the same to slip in the friction-clamp as here- 30 tofore and the wick to be carried to a lower point.

This device is exceedingly simple, is easily applied, the extent of tension upon the clamp device may be varied by an ordinary screw- 35 driver turning down the screw 4, and the said friction-clamp may be employed at any convenient place along said shaft where it is adapted to come into engagement or contact with the body of the lamp in opposite positions to arrest the movement.

I claim as my invention—

1. In a wick-raiser, the combination with a shaft and a rack and pinion, of a device frictionally held to said shaft and ordinarily 45 adapted to arrest the movement of said shaft in raising and lowering the wick, and the relation of which device to the shaft may be al-

tered by the application of additional force to the shaft for adjusting the position of the wick.

2. In a wick-raiser, the combination with a shaft, a pinion and rack, of a device surrounding, supported by and frictionally held to said shaft and ordinarily adapted to arrest the movement of the shaft and regulate the extreme positions of the wick, and the relation of which device to the shaft may be altered by the application of additional force to the shaft for adjusting the position of the wick.

3. In a wick-raiser, the combination with the body of the lamp, a shaft, a pinion, suitable bearings for the shaft and a rack engaged by the pinion, of a friction-clamp comprising a sleeve surrounding said shaft and having lug extensions and a device passing through 65 the lug extensions to draw and hold them together and hold the sleeve with force to the shaft, substantially as set forth.

4. In a wick-raiser, the combination with the body of the lamp, a shaft, a pinion and a 70 rack for raising and lowering the wick, of a tubular support surrounding a portion of said shaft and secured to the body of the font with its inner free end adjacent to the pinion, a bearing-bracket connected to the body 75 of the lamp and through which the shaft passes, the said tubular support and bracket coming at the opposite sides of the pinion for guiding the same, a bearing in the body of the lamp for the end of the shaft, and a friction-clamp upon and surrounding said shaft and coming between the bearing-bracket and the end bearing of the shaft and adapted to arrest the movement of the shaft with the extreme movements of the wick, and the relation of which device to the shaft may be altered by the application of additional force to the shaft for adjusting the position of the wick.

Signed by me this 20th day of April, 1903. 90
WILLIAM W. BRADLEY.
